[57] CLAIM

The ornamental design for a combined garment display
arm and mounting bracket, substantially as shown.

DESCRIPTION

FIG. 1 is a perspective view of a combined garment display
arm and mounting bracket showing my new
design;

FIG. 2 is a front elevational view, the rear being a mirror
image thereof;

FIG. 3 is a fragmentary, top plan view thereof;

FIG. 4 is a fragmentary, bottom plan view thereof.
